ART OF MAKING LACE CURTAINS

James Waterfield, Philadelphia, Pa., assignor to
 Quaker Lace Company, Philadelphia, Pa., a corporation of Pennsylvania

Application October 30, 1934, Serial No. 750,667

4 Claims. (Cl. 2—278)

This invention relates to improvements in the art of making lace curtains.

An object of the invention is to provide a curtain of novel construction having a two ply border portion simulating a hem but differing therefrom by presenting a non-straight or sinuously formed free edge for improving the appearance and enhancing the beauty of the curtain.

Another object is to provide a novel construction and arrangement of parts wherein the outer edge portion of the plies of the border portion are connected and finished in a manner to lend strength, durability and attractiveness to the curtain.

15 Another object is to provide a novel construction and association of parts wherein the outer edges of the two ply border portion are secured together by over-edge thread stitches which enclose a cord and form a strong and durable 20 foundation for the immediately adjacent weaker parts of the lace fabric and wherein a second cord laterally adjacent and in close proximity to the first named cord is secured to such parts by thread stitches and provided with outwardly extending embellishing loops which cross the cord 25 enclosed by the over-edge thread stitches.

A further object of the invention is to provide a novel and advantageous art or method of making a lace curtain having the characteristics 30 above set forth.

With the foregoing and related objects in view, the invention resides in the novel art of making the curtain as will be hereinafter described and claimed.

35 In the accompanying drawings, illustrating the invention,

Figure 1 is a front view of a curtain containing the invention.

Figure 2 is a front view of an edge portion of 40 the curtain, enlarged.

Figure 3 is a section through an edge portion of the curtain, enlarged, on line 3—3 of Fig. 1.

Figure 4 is a front view of a part of an edge portion of a length of lace fabric employed in 45 constructing the curtain shown in Fig. 1.

Figure 5 is a front view of the fabric shown in Fig. 4, showing the condition thereof after the same has been folded and stitched to produce a hem thereon.

50 Figure 6 is a front view of the fabric, showing the condition thereof after the same has been hemmed, as shown in Fig. 6, and after a part or parts of the free edge portion of the hem has been cut and over-edge thread stitches have been applied to the remaining two plies of the cut hem.

Figure 7 is a front view of the fabric, showing the condition thereof after the same has been hemmed and cut and had the cord and over-edge thread stitches applied to the plies of the hem and after a second cord has been applied and stitched to the fabric adjacent to the over-edge stitches and the cord enclosed therein, the illustration being an enlargement of the portion of the completed curtain embraced by the line 7—7 in Fig. 1.

10 Figures 8 and 9 are sections through the fabric, on lines 8—8 and 9—9 of Figs. 5 and 6, respectively.

Referring to the drawings, 2 designates the body of the curtain which is formed of suitable 15 lace fabric, such, for example, as "Nottingham lace".

The body of the curtain has a two ply border portion 4 extending along one side thereof and along the bottom thereof.

20 One ply 5 of the border portion 4 is formed of and constitutes a continuation of the main body 2 of the curtain, and the other ply 6 of the border portion is formed of suitable lace fabric.

The fabric of the main body 2 including the 25 part thereof which forms the ply 5 of the border portion 4, is formed of a ground-work of open mesh interrupted by areas 10 of fabric of greater density constituting design forming figures for 30 ornamenting the curtain, and the ply 6 of the border portion is, preferably, formed entirely of open mesh fabric.

The inner edge portion of the ply 6 of the border portion of the curtain is folded and secured to the main body 2 of the curtain by suitable 35 thread stitches 11.

The outer edges of the two plies 5 and 6 of the border portion may be of any desired coinciding or matched configuration, and, in accordance with the advantages of my invention, such configuration may be non-straight and of the sinuous form illustrated in the drawings. The adjacent outer edge portions of the two plies are enclosed within and secured together by over-edge thread stitches 12 which penetrate the 45 plies and enclose a cord 13 with the edge portions thereof.

The fabric from which the curtain is made is woven so that the edge of at least one of the plies of the border portion whose edge portion is enclosed by the thread stitches 12 will be of greater 50 density than the open mesh portions of the fabric and of a character like the fabric of the areas 10 which form the design figures. In the fabric of the curtain herein illustrated, the edge 55

portion of the ply 5 which is enclosed by the thread stitches 12 is of a character like and forms a continuation of the fabric which forms the design figures 10, such figures having portions which follow the sinuous line of the outer edge of the border portion 4.

The outer edge portion of the border portion 4 has a cord 14 applied to the outer surface of the ply 5 thereof, and this cord 14 is secured to the border portion by suitable thread stitches 15 which penetrate the two plies 5 and 6 and enclose the cord 14. The cord 14 extends laterally adjacent and in close proximity to the over-edge thread stitches 12 and the cord 13 enclosed thereby. The cord 14 follows the sinuous line of the outer edge of the border portion 4 and it is provided, at suitably spaced intervals, with embellishing, free loops 16 which extend outwardly from the line of thread stitches 15 and cross and 20 extend beyond the over-edge stitches 12 and the cord 13 enclosed thereby.

Those portions of the fabric immediately adjacent to but outside of the over-edge stitches 12 may be, in whole or in part, formed of open mesh 25 or fabric of greater density. In either case the edge portions of the plies 5 and 6 and the cord 13 and the stitches 12 enclosing them provide a foundation which lends strength and durability to the portions of the plies to which the cord 14 is secured, thereby permitting any desired variation 30 in the open mesh ground-work and design forming figures of greater density by permitting either of them to extend to the cord 14 in accordance with the design produced in the lace fabric 35 of the curtain. Thus it will be understood that the employment of the two cords 13 and 14 and their associated stitches 12 and 15, respectively, and the parts of the two plies of the border portion of the curtain to which they are attached 40 provides a free edge for the border portion which may have any desired contour and which is not only strong and durable and ornamental but which will permit any desired variation in the design of the lace fabric of the curtain.

In producing a curtain constructed in accordance with my invention, I produce a suitable length of lace fabric which is wider and longer than the finished curtain to be produced therefrom, and I use the excess width and length for 45 the production of a hem on one side thereof and on the bottom thereof as one step in the art of producing my improved curtain, and, as the subsequent operations on the two hem are the same I shall describe such operations only in connection 50 with the side hem.

In Fig. 4 of the drawings the excess width in the length of fabric from which the curtain illustrated in the drawings is produced is designated by the numeral 21 and it is that portion of the fabric shown in Fig. 4 which is on the right hand side of the vertical line 17-17.

After the length of lace fabric with this excess width 21 is produced, the fabric is folded on the line 17-17, the free edge portion of the part 21 thereof is folded inwardly and secured to the main body of the fabric by the line of thread 65 stitches 11, thereby producing a side hem 18 in the fabric, as illustrated in Figs. 5 and 8.

The design forming figures 10 of the fabric are 70 so related to the parts of the hem 18 that they appear only on the forward ply of the hem and they include sinuously formed parts 19 which extend along the free edge portion of the hem 75 inwardly of the fold thereof which constitutes

the straight free edge of the hem, as shown in Fig. 5.

After the hem 18 has been produced, as just described, the portions 20 of the hem 18 which extend outwardly from the sinuously formed parts 19 are severed from the main body of the hem by cutting the two plies of the hem between the fold thereof and such parts and in close relation to such parts, and the remaining edge portions of the hem plies are secured together by the 10 application thereto of the over-edge thread stitches 12 which penetrate and enclose the outer portions of the parts 19 and follow the sinuous line formed thereby, as shown in Fig. 6. The stitches 12 are applied immediately following the 15 cutting of the hem plies and they are applied as rapidly as the stitches are applied by a suitable fabric cutting and sewing machine; and, as rapidly as the stitches 12 are applied, the cord 13 is fed to the edge portions of the hem plies and 20 enclosed with the same within the stitches 12, as shown in section in Fig. 3. The cord 13 extends within the stitches 12 throughout the entire sinuously formed edge portion of the curtain.

After the hem plies have been cut to form the 25 two plies 5 and 6 of the border portion 4 of the finished curtain, and after the over-edge stitches 12 and the cord 13 have been applied to the plies, as above described, the second cord 14 is applied to the outer surface of the ply 5 laterally adjacent 30 and in close proximity to the cord 13 and the over-edge stitches 12 enclosing the same, and this second cord 14 is secured to the border portion 4 of the curtain by the thread stitches 15 which 35 penetrate the two plies of such portion and enclose the cord 14. The stitches 15 are produced by a suitable sewing machine which is provided with means for feeding the cord 14 to the stitches during the production thereof, and, at certain spaced intervals throughout the line of stitches 40 15 the embellishing loops 16 are formed in the cord. These loops extend outwardly from the line of stitches and cross the cord 13 and the over-edge stitches 12 enclosing the same, as illustrated in the drawings, and the loops 16 may conveniently be formed by a means in the sewing machine which produces the stitches 15 and feeds the cord 14 thereto.

I desire it to be understood that the side and bottom border portions of the curtain are alike 50 or substantially alike in construction and that either of such portions may be omitted without departing from my invention.

I claim:

1. The art of producing a lace curtain which 55 consists in producing a length of lace fabric, producing a hem on one edge portion of the fabric by folding the same and securing it to the main body of the fabric by the application of thread stitches thereto, severing a portion of the hem from the 60 main body thereof by cutting the two plies of the hem inwardly of the fold thereof, and securing the remaining edge portions of the plies of the hem together by the application of over-edge thread stitches thereto.

2. The art of producing a lace curtain which 65 consists in producing a length of lace fabric having a ground-work of open mesh and design forming figures of greater density than the ground-work and including sinuously formed 70 parts extending along but spaced from an edge of the fabric, producing a hem on the edge portion of the fabric containing said sinuously formed parts by folding said portion and stitching it to the main body of the fabric by a sewing operation, 75

severing a portion of the hem from the main body thereof by cutting the two plies of the hem between the fold thereof and said sinuously formed parts by a cutting operation following 5 the lines of said parts, and securing the remaining edge portions of the two plies of the hem together by the application of over-edge thread stitches thereto.

3. The art of producing a lace curtain which 10 consists in producing a length of lace fabric, producing a hem on one edge portion of the fabric by folding the same and securing it to the main body of the fabric by the application of thread stitches thereto, severing a portion of the hem 15 from the main body thereof by cutting the two plies of the hem inwardly of the fold thereof, applying a cord to the remaining edge portions of the plies of the hem, and securing said cord and said remaining edge portions together by the 20 application of over-edge thread stitches thereto.

4. The art of producing a lace curtain which consists in producing a length of lace fabric having a ground-work of open mesh and design forming figures of greater density than the ground-work and including sinuously formed parts extending along but spaced from an edge of the fabric, producing a hem on the edge portion of the fabric containing said sinuously formed parts by folding said portion and stitching it to the main body of the fabric by a sewing operation, 10 severing a portion of the hem from the main body thereof by cutting the two plies of the hem between the fold thereof and said sinuously formed parts by a cutting operation following the lines of said parts, applying a cord to the remaining 15 edge portions of the plies of the hem, and securing said cord and said remaining edge portions together by the application of over-edge thread stitches thereto.

JAMES WATERFIELD. 20
